UNITED STATES PATENT OFFICE.

DAVID JOHN MORGAN, OF CAERACCA, SOUTH WALES.

TURBINE.

Application filed September 5, 1925, Serial No. 54,830, and in Great Britain September 10, 1924.

My invention relates to improvements in turbines of the type in which a rotor having a number of radial vanes is enclosed in a suitable casing in such a manner that steam projected upon the vanes will cause the rotor to turn about suitable bearings so as to convert the energy of the steam into motive power.

The object of this invention is to provide a simple and improved construction of this type of turbine and especially to ensure an effective fluid tight joint between the vanes and the casing.

In order that my invention may be clearly understood, reference is made to the accompanying drawings, in which:—

Fig. 1 shows in elevation a spherical form of rotor of a turbine constructed according to my invention.

Fig. 2 is an end elevation of the turbine showing a portion of the casing broken away to disclose the rotor in position therein.

Fig. 3 is a part sectional elevation showing one of the radial vanes and packing strips and the manner of distributing the fluid pressure to the back thereof.

Fig. 4 is an end elevation of the vane shown in Fig. 3, and

Figs. 5 and 6 are transverse sections through the steam distributing pocket, and showing the valve in its two alternative positions.

Referring to the drawings, the rotor 1 is shown of cylindrical form having a number of radial vanes 2 formed by providing transverse recesses 3 extending across the periphery of the rotor. The rotor is mounted upon a suitable shaft 4 supported in bearings 5 in an outer casing 6, the interior of which corresponds to the spherical shape of the rotor 1. The radial vanes 2 are a comparatively loose fit in the casing 6 and curved packing strips 7 are located in transverse grooves extending across the periphery of each of the vanes 2 and over the surface of the rotor itself close down to the shaft 4. These packing strips 7 correspond in shape to the inner surface of the casing 6 and press lightly against it. Means are provided to admit fluid pressure to the back of these packing strips so as to hold them tightly against the inner face of the casing, whilst the vane is subjected to the pressure fluid, thus ensuring an effective joint with the casing.

The packing strips 7 which may be of the section shown in Figs. 5 and 6, engage in grooves 8 in the periphery of the vanes 2, and portions of the rotor 1 and a series of 60 passages 9 extend from the back of each packing strip 7 to a steam pocket 10 formed in the thickness of each vane 2. Each steam pocket is formed in a suitable flanged seating 11 held in place in an opening 12 extending through the vane 2 by means of a loose flange 13 bolted or otherwise secured upon the opposite side. In each seating is formed the pocket 10 from which the passages 9 radiate to the groove 8 so as to permit fluid pressure to force the packing strip 7 against the casing 6. Ports 14 extend from each side of the seating 11 to the pocket 10 and a hinged flap valve 15 in each pocket is adapted to engage over either of the ports 14 as illustrated in Figs. 5 and 6. In the casing 6 is provided a fluid pressure inlet 16 arranged substantially in a tangential position to the periphery of the rotor and so that the fluid pressure therefrom will 70 impinge directly upon each of the vanes 2 as the rotor turns upon its axis. When the vane is at one side of the inlet port 16 for the fluid pressure, the valve 15 will engage over one of the ports 14 in the vane so as to prevent the escape of the fluid pressure therethrough. The vane in front which has already passed the port 16 will have its valve 15 engaging over the other port 14 75 so as to prevent the passage of the pressure fluid therethrough. The passages 9, however, in both these vanes will receive pressure fluid from the pockets 10 so as to force their packing strips 7 against the periphery 80 of the casing and ensure a fluid tight joint, and preventing the escape of the fluid pressure from the chamber 3. A suitable outlet or exhaust port 17 is also provided in the casing to permit the escape of the pressure fluid after it has expended its energy 85 upon the vanes of the turbine. The turbine may be readily operated in the reverse direction by admitting pressure fluid through port 17 and exhausting through 16. Any 90 number of turbines may be connected in series so as to allow the steam or other pressure fluid to expand in several stages. The rotor and casing may be formed so that the vanes are of substantially rectangular shape 95 with rounded outer corners.

My improved turbine is of a simple nature with few moving parts. Each vane receives

the force of the incoming fluid directly in turn so that the rotor will move continuously in one direction, and the packing strips extending transversely across each vane and close down to the shaft about which the rotor turns, affords an effective seal to prevent escape of the pressure fluid.

I claim:

1. In a turbine, a rotor of generally spherical form, a casing of corresponding shape enclosing the rotor and having tangentially disposed inlet and outlet ports, a series of vanes formed on the rotor, packing strips extending across the vanes and the surface of the rotor, a pocket in each vane to which fluid pressure is admitted, a series of passages from the pocket in each vane to the back of the groove in which its packing strip engages, ports leading into the pocket from each side of the vane and at least one valve located between the ports and adapted to close each alternately.
2. In a turbine, a rotor of generally spherical form, a casing of corresponding shape enclosing the rotor and having tangentially disposed inlet and outlet ports, a series of vanes formed on the rotor, packing strips extending across the vanes and the surface of the rotor, a flanged seating engaging in a through aperture in each vane, a loose flange in the opposite side of the vane and secured to the flanged seating, passages leading from the pocket to the groove in which the packing strip of each vane is located and means for admitting pressure fluid to the pocket to force the packing strip outwardly against the periphery of the casing.
3. In a turbine, a rotor of generally

spherical form, a casing of corresponding shape enclosing the rotor and having tangentially disposed inlet and outlet ports, a series of vanes formed on the rotor, packing strips extending across the vanes and the surface of the rotor, ports leading into the pocket from each side of the vanes, a valve located between the ports and adapted to close each alternately, a flanged seating engaging in a through aperture in each vane, a loose flange on the opposite side of the vane and secured to the flanged seating, passages leading from the pocket to the groove in which the packing strip of each vane is located and means for admitting pressure fluid to the pocket to force the packing strip outwardly against the periphery of the casing.

4. In a turbine, a rotor of generally spherical form mounted to rotate upon a transverse shaft, a casing of corresponding shape and having tangentially disposed inlet and outlet ports, a series of vanes formed on the rotor by means of transverse recesses in the face thereof, transverse grooves extending across these vanes and the face of the rotor close up to the shaft, packing strips located in these grooves, a flanged seating located in a through aperture in each vane, a loose flange secured to the seating to retain it in position, ports in the seating communicating with opposite sides of each vane, and a valve between the ports adapted to seat over and close either port alternately leaving the other open to admit fluid pressure to the pocket from one side of the vane at a time.

DAVID JOHN MORGAN.
